C. G. MILLER,
ARTIFICIAL CHRISTMAS TREE,
APPLICATION FILED APR. 10, 1917.

1,252,922.

Patented Jan. 8, 1918.

UNITED STATES PATENT OFFICE.

CHARLES G. MILLER, OF LEE, MASSACHUSETTS.

ARTIFICIAL CHRISTMAS TREE.

1,252,922.

Specification of Letters Patent.

Patented Jan. 8, 1918.

Application filed April 10, 1917. Serial No. 161,007.

To all whom it may concern:

Be it known that I, CHARLES G. MILLER, a citizen of the United States, and resident of Lee, in the county of Berkshire and State 5 of Massachusetts, have invented certain new and useful Improvements in Artificial Christmas Trees, of which the following is a specification.

This invention relates to new and useful 10 improvements in artificial trees, and more particularly to artificial Christmas trees, that are adapted to act as a substitute for natural trees, and which are formed with an outer stationary frame holding either 15 artificial or natural branches, and an inner rotary decoration supporting frame, which makes the tree very attractive for display purposes.

Another object of the invention is to provide 20 a device of this character which is easily and simply constructed, inexpensive to manufacture, and one which will be very efficient in operation.

With these and numerous other objects in 25 view my invention consists of the novel features of construction, combination and arrangement of parts which will be herein referred to and more particularly pointed out in the specification and claim.

30 In the accompanying drawing:

Figure 1 is a vertical section through the artificial tree, and

Fig. 2 is a horizontal section of the same.

In describing my invention I shall refer 35 to the drawing in which similar reference characters designate corresponding parts throughout the several views. The numeral 1 designates a base or support for the tree, on which is mounted a stationary outer 40 frame designated in its entirety by the numeral 2, that is adapted to receive a plurality of either artificial or natural branches, and a rotary inner frame 3, that is adapted to support a plurality of decorations. The 45 base 1 is provided with means including an upright shaft 4, upon which the inner frame is mounted, and said shaft being revolved to rotate the inner frame within the outer frame to present a very attractive appearance to the tree.

The base 1 is formed in two portions the base or support proper 5 being adapted to rest on the ground, while spaced vertically therefrom is an upper top 6 upon which the outer stationary frame is positioned. The 55 top 6 is a plate of any desired configuration,

preferably circular, and the same is connected with the bottom 5 by a plurality of supporting legs 7.

The stationary frame 2, that is the outer 60 frame of the device, comprises a plurality of spaced standards 8 that have their lower ends mounted in the top 6 of the base 1, in spaced relation adjacent the marginal edge thereof. The standards are circumferentially 65 spaced around the top, and each of the standards is provided with a plurality of apertures 9 therein, adapted to receive the inner ends of either natural or artificial branches 10, so as to give the device the appearance of a natural tree. The standards 8 are inclined inwardly, and the branches are 70 preferably so arranged, as to slope correspondingly to give the appearance of a conventional type of Christmas tree, as 75 clearly shown in Fig. 1 of the drawing. The upper ends of the standards 8 are connected by a top plate 11, that will securely hold them in position.

Mounted in the base 1 is the rotatable upright shaft 4, which has its lower end provided with a projecting pin 12 that is adapted to be received in a glass bearing 13 countersunk centrally in the upper surface of the bottom 5 of said base. The shaft 4 projects 80 upwardly through the top 6, and the top plate 11 of the outer frame 2, alining openings being provided in these parts for the same. A spring motor, preferably a clock work that is designated by the numeral 14 85 is positioned in said base, and the projecting pinion 15 thereof is adapted to intermesh with a driving gear 16 carried by the shaft 4. By this means upon the operation of the spring motor, the shaft 4 will be rotated accordingly. If desired however the motor 90 may be eliminated, and any other desired type of driving means may be employed to rotate the shaft 4.

The inner decoration supporting frame 3 100 comprises a plurality of spaced partitions 17, that are preferably star-shaped, and which are secured in longitudinally spaced relation on the shaft 4 within the outer frame 2. These partitions 17 are connected 105 by stays 18 secured therethrough adjacent the points of the stars, as clearly shown in Fig. 2 of the drawing. The stays 18 are adapted to receive any type of decorations as may be desired, the decorations being designated thereon by the numeral 19.

In operation when the various parts of

this device are assembled as shown in the accompanying drawing, it will be obvious that upon operation of the spring motor the shaft 4 will be rotated, and consequently the 5 inner decoration supporting frame that is carried thereby will be revolved within the outer frame. The outer frame is decorated with natural or artificial branches so as to give the device the appearance of an ordinary tree, and the revolving decoration holding inner frame therein will greatly add to the attractiveness of a device of this character. The artificial tree is especially adapted for display purposes, wherein the revolvable inner frame may be provided with lights 15 that will shine through the branches carried by the stationary outer frame. The projecting ends of the rotatable shaft 4 that extends from the top 11 is also provided with 20 a plurality of branches thereon so as to conform to the shape of the type of tree which the device is supposed to represent.

It will be understood that while in the accompanying drawing the standards of the stationary frame are provided with a plurality of apertures to receive the ends of the branches, if desired any other fastening means may be employed to accomplish this purpose. Also the decorations 19 may be 25 secured to the stays in any manner, and they may be attached to any part of the rotating inner frame as desired. The glass bearing in the base 1 allows the shaft 4 to 30

rotate freely and as has been hereinbefore stated the driving means of this shaft need 35 not necessarily be the clock work mechanism as shown in the accompanying drawing, as any other available means may be employed.

From the foregoing description of the construction and operation of my artificial 40 Christmas tree, the manner of applying the same to use and the operation thereof will be readily understood, and it will be seen that I have provided a simple and efficient means for carrying out the objects of this 45 invention.

Having thus fully described my invention, what I claim as new, and desire to secure by Letters Patent, is:

A device of the class described comprising 50 a base, a stationary outer frame including a plurality of spaced branch supporting standards carried by said base, an upright shaft having its lower end rotatably mounted in the base and extending upwardly through 55 the outer frame, a plurality of longitudinally extending spaced partitions on said shaft within the outer frame, spaced stays extending through said partitions adjacent the marginal edges thereof and adapted to 60 receive decorations thereon, and means carried by the base for rotating said upright shaft.

In testimony whereof, I affix my signature hereto.

CHARLES G. MILLER.
